CLAIM

The ornamental design for a modular shelving unit, as shown and described.

DESCRIPTION

FIG. 1 is front view of a modular shelving unit showing our new design;

FIG. 2 is left side view of the design shown in FIG. 1;
 FIG. 3 is a right side view of the design shown in FIG. 1;
 FIG. 4 is a front right perspective view of the design shown in FIG. 1;

FIG. 5 is a front left perspective view of the design shown in FIG. 1; and,

FIG. 6 is a top view of the design shown in FIG. 1.
 The bottom and rear of the modular shelving unit forms no part of the claimed design. The broken lines shown in the figures are included for the purpose of illustrating portions of the modular shelving unit and form no part of the claimed design.

1 Claim, 6 Drawing Sheets---
